Primary Examiner — Kendra Leslie Hamilton

(57) **CLAIM**

The ornamental design for a teething mitten, as shown and described.

DESCRIPTION

FIG. 1 is a front elevational view of a teething mitten showing my new design;

FIG. 2 is a rear elevational view thereof;

FIG. 3 is left side view thereof;

FIG. 4 is a right side view thereof;

FIG. 5 is a top plan view thereof;

FIG. 6 is a bottom plan view thereof;

FIG. 7 is a top, front and right side perspective view thereof;

FIG. 8 is a front perspective view thereof;

FIG. 9 is a left side perspective view thereof; and,

FIG. 10 is a bottom, front and right side perspective view thereof.

In the drawings, the broken lines indicate boundaries of the claimed design.
